ELECTRODE HOLDER

Wilbur A. Robb, Huntington Park, Calif.

Application October 30, 1937, Serial No. 171,873

7 Claims. (Cl. 176—119)

My invention relates to electrode holders, and more particularly to holders for carbon electrodes for motion picture projecting machines.

An important object of the invention is to provide means for holding such a carbon electrode until it is almost completely consumed. Under present practice, carbon electrodes, that have been used for about three or four reels of motion picture film, often have to be thrown away even though there is still sufficient carbon left to last for another reel of film.

The reason for this lies in the construction and arrangement of carbon holders on motion picture projecting machines now in general use. It is an object of my invention to provide a carbon holder that will reduce this waste to a minimum, whereby considerable saving can be effected by moving picture theaters in the quantity of carbon electrodes utilized in the operation of their projection machines.

Still another object is to provide such a holder for the positive carbon of a motion picture projection machine, which carbon is consumed faster than the negative one.

The invention also comprises novel details of construction and novel combinations and arrangements of parts, which will more fully appear in the course of the following description.

In the drawing, like reference characters designate similar parts in the several views.

Figure 1 is an elevation of an electrode carrier of a motion picture projection machine, to which carrier has been applied my electrode holder.

Figure 2 is a section through a stem of my holder, taken on the line 2—2 of Figure 1, looking in the direction of the arrows.

Figure 3 is a section through my holder, taken on the line 3—3 of Figure 1, looking in the direction of the arrows.

Figure 4 is a section through my holder, taken on the line 4—4 of Figure 1, looking in the direction of the arrows.

Figure 5 is a bottom view of my electrode holder.

Figure 6 is a perspective view of my electrode holder.

Figure 7 is a perspective view of a portion of a motion picture projection machine.

Referring more in detail to the drawing, the reference numeral 7 designates a support on a motion picture projection machine for a positive carbon electrode holder. A fixed jaw 8 is mounted on the support, while a movable jaw 9 is disposed in clamping arrangement with the jaw 8.

An apertured block 11 is mounted on the support 7 at the rear of the jaws 8, 9.

A sleeve 12 on the support provides a bearing for a handle 13. The handle is connected to operate the movable, clamping jaw 9. An arm 14 on the support 7 maintains the sleeve 12 on the support in relatively fixed position. The handle 13 and the sleeve 12 have a threaded engagement (not shown).

A conductive cable 15 is connected with the support 7, to conduct positive electrical current to the holder.

A stationary electrode guide 16 has a notched top 17 for directing positive carbon electrode 18 as it is fed forward into operative association 15 with a negative carbon electrode 19. An ash receiver 20 is disposed beneath the ends of the two electrodes 18, 19, to catch ashes falling therefrom.

The support 7 is a movable support, to feed forward the positive carbon electrode. Conventional parts of a motion picture projection machine are illustrated in relatively light, unshaded lines, in the drawing. Since the details of construction of the ordinary motion picture projection machine are well known in the trade, further illustration and description are deemed unnecessary.

My holder, generally designated 10, includes a stem 22 that is substantially square in section. The rear end of the stem 22 is inserted in the aperture in the block 11 and the forward end of the stem is clamped in place between the jaws 8, 9. At the outer end of the stem 22 is a collar 23. Beyond the collar is a head 24 that is triangular in cross section.

End face 25 of the head 24 has a cylindrical recess 26. The recess is of sufficient diameter to require side openings 27 to be cut out at the sides 28 of the head 24. These side cut-away portions 27 are of sufficient size for a cylindrically shaped carbon electrode in the holder 10 to be either flush with the sides 28 of the head, or to extend beyond the sides 28. The function of this arrangement is that the carbon electrode 18 may thereby ride against the surfaces of the notch 17 even though my holder is employed.

Continuing rearward from the recess 26, the head 24, the collar 23 and the stem 22 have a continuous slot 29.

In the use of my invention, when a carbon electrode has been used until its length has been substantially reduced, the end of the remainder is inserted into the recess 26 and the rear end of the stem 22 is inserted in the aperture in the block 11. The split, forward end of the stem 25

is disposed between the jaws 8, 9. Rotation of handle 13 causes the movable jaw 9 to be moved toward the fixed jaw 8, thus clamping the portions of the split end of the holder about the 5 end of the carbon electrode. The pressure of the movable jaw upon the split end places the latter under pressure, thus maintaining my holder in place.

It will be noted that my holder does not interfere with the carbon seating in the notch 17, 10 for the carbon engages the notch 17 through the slots 21.

When the holder 10 has been fed forward to its limit (as shown in broken lines in Figure 1), 15 the collar 23 engages the outer face of the guide 16, thus preventing further forward movement of the support 7.

While I have illustrated and described what I now regard as the preferred embodiment of my 20 invention, the construction is, of course, subject to modifications without departing from the spirit of my invention. I, therefore, do not wish to restrict myself to the particular form of construction illustrated and described, but desire to 25 avail myself of all modifications which may fall within the scope of the appended claims.

Having thus described my invention, what I claim and desire to secure by Letters Patent is:

1. In a motion picture projection machine having a guide for an electrode and having a movable support for feeding the electrode while being directed by the guide, a holder on the support, and a member on the holder for receiving the electrode, the member being arranged to 30 move along the guide during advancing movement of the support, and a side of the member being cut away sufficiently for the portion of the carbon within said member to ride directly on the guide during said advancing movement of the support.

2. In a motion picture projection machine having a guide for an electrode and having a movable support for feeding the electrode while being directed by the guide, a holder on the support, and a member on the holder for receiving the electrode, the member substantially conforming 35 with the shape of the guide and being arranged to advance along the guide during advancing movement of the support, and a side of the member being cut away for the carbon to ride directly on the guide during said advancing movement of the support.

3. In a motion picture projection machine having an angularly notched guide for an electrode and having a movable support for feeding the electrode while being directed by the guide, a holder on the support, and an angularly shaped member on the holder substantially conforming 40

with the shape of the notch in the guide and being arranged to advance along the guide during advancing movement of the support, and the angularly arranged faces of the member being cut away for the carbon to ride directly on the guide 5 during said advancing movement of the support.

4. In a motion picture projection machine having a guide for an electrode and having a movable support for feeding the electrode while being directed by the guide, a holder on the support, a collar on the holder arranged to engage the guide and thereby limit the movement of the holder, and means on the holder for gripping an end of an electrode, said means being arranged ahead of the collar and being disposed 10 to move along the guide.

5. In a motion picture projection machine having a guide for an electrode, having a movable support for feeding the electrode while being directed by the guide, and having relatively fixed 20 and movable jaws, a holder on the support, a collar on the holder arranged to engage the guide and thereby limit the movement of the holder, a head on the holder shaped to move along the guide until the collar engages same, the head 25 and collar being split and the portion of the holder at the end of the split being of unitary construction to provide resilience to the holder, the head being recessed to receive the end of an electrode, and the holder being arranged between the fixed and movable jaws of the machine for said jaws to clamp the split head upon an end of an electrode.

6. In a motion picture projection machine having a guide for an electrode and having a movable support for feeding the electrode while being directed by the guide, a holder on the support for receiving the electrode, the holder being arranged to move along the guide during advancing movement of the support, the holder 40 having a recess to receive an electrode and the recess having an opening in a side thereof, and an electrode disposed in the recess and extending through the opening in the side of the recess at least to the outer surface of the holder.

7. In a motion picture projection machine having a support for progressively feeding an electrode and having a guide provided with a differently shaped notch than the electrode to direct the electrode, a holder on the support for receiving the electrode, the holder being arranged to bottom in the notch, the holder having a recess to receive an electrode and the recess having an opening in a side thereof, and an electrode disposed in the recess and extending through the opening in the side of the recess and into engagement with the notch.
